(57) **CLAIM**

The ornamental design for a hand held and neck hanging fan, as shown and described.

DESCRIPTION

FIG. 1 is a front, right and top perspective view of a hand held and neck hanging fan, showing my new design;
FIG. 2 is a rear, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof; and,
FIG. 8 is a bottom plan view thereof.

The broken lines shown in the drawings illustrate portions of the hand held and neck hanging fan that form no part of the claimed design.
